UNITED STATES PATENT OFFICE.

WILHELEM PROCHNOW, OF MILWAUKEE, WISCONSIN.

MORTAR-MIXER.

SPECIFICATION forming part of Letters Patent No. 295,196, dated March 18, 1884.

Application filed January 29, 1884. (No model.)

To all whom it may concern:

Be it known that I, WILHELEM PROCHNOW, of Milwaukee, in the county of Milwaukee, and in the State of Wisconsin, have invented 5 certain new and useful Improvements in Mortar-Mixers; and I do hereby declare that the following is a full, clear, and exact description thereof.

My invention relates to mortar-mixing machines, and will be fully described hereinafter.

In the drawings, Figure 1 is a side elevation of my machine connected with a horse-power motor and ready for work. Fig. 2 is a top view of the same. Fig. 3 shows a longitudinal vertical section of part of the machine, and Fig. 4 is an enlarged top view of one of the mixing-knives.

A is the mixing-box, which may be mounted on its own wheels, *aa*, (shown in dotted lines) 20 or on any form of detachable supports, *A' A'*. A door, *B*, fitted with a suitable latch, *a'*, is hinged in the center of either one of the box sides, for convenience in filling in the materials as well as emptying the mortar. Bolted in 25 the upper edge of the box sides are the standards *b b' b' b*, on top of which are laid the rails *c c*, firmly bolted thereon. The end standards, *b b*, have extensions *b' b'*, securely fastened therewith, and to the upper end of which 30 are bolted the upper rails, *c' c'*, and between these rails *c' c'* and the lower one, *c c*, are mounted two pair of flanged wheels, *C C* and *C' C'*, both of said wheels being made of a diameter to run loosely between said rails 35 *c* and *c'*, this latter being intended as a guard-rail for the wheels. Each pair of wheels runs on the journaled ends of a square axle, *D D'*, and the journals of the axle *D* are extended out to be connected by pitmen *E E* to the crank 40 of the driving-wheel *F* of the motor used, these pitmen *E E* and their attachment to the wheel being obviously proportioned to the length of the box *A*. The square axles *D* and *D'* carry the mixing-knives *e e e e' e' e' e' e'*. 45 These knives consist of the body *e* and the stem *e'*, projecting upward from the center of said body, edges of which are given a suitable point to cut either way through the material to be mixed. The stem *e'* of the knives 50 is connected to the square axles *D* and *D'* by means of a clamp, *d*, firmly bolted thereon,

and a nut, *d'*, working in the upper threaded end of said stem *e'* and against the collar *d'* of the same, serves to tighten the knife in said clamp *d*. The knives are attached so as to 55 alternate together on both sides of the axles, and their lower end works close to the bottom of the box *A*. The axles *D* and *D'* are maintained at a certain distance from each other and are connected by means of the bars or 60 rods *f f*, one end of which hinges in any suitable manner in *D*, and its opposite end is bent down to hook in the eye of a staple, *g*, of the axle *D'*. This connection allows of bringing the two axles together at the end of 65 the box *A* nearest to the motor, to facilitate the filling in of the materials and the emptying of the mortar, the bar *f* and the knives on axle *D*, shown in dotted lines in Fig. 3, illustrating their position in relation to the 70 knives of axle *D'* without regard to the box itself.

The operation of my machine may be readily understood from the above description. The mixing of the mortar is speedily and ef- 75 ficiently produced by the back-and-forth motion given to the knives in the whole length of the mixing-box. The double pointed knives are constantly brought in contact with different parts of the mass, every particle of 80 which is thrown to one side or the other of the knives until perfect homogeneity has been attained. This is obtained with my machine very promptly and at much less expense, as well as with much greater thoroughness than 85 by ordinary hand-work.

I have represented my machine connected with a horse-power machine, as this motor is the one apparently the best adapted to the driving of a portable mortar-mixing machine, 90 but obviously any other motor may be used, if desired; and it must also be understood that I do not restrict myself to the particular form of box or the manner of attachment of the knives shown and described, as these may be 95 varied considerably without departing from the spirit of my invention.

Having thus described my invention, what I claim as new, and desire to secure by Letters Patent, is—

In a mortar-mixing machine, the box *A*, having the hinged door *B*, supports *b b' b'* for

the rails $c\ c$, and extensions $b^2\ b^2$ for the guard-rails $c'\ c'$, in combination with the wheels C C and C' C', axles D and D', bearing the knives e e e e' e' e', bars or rods f f, and pitmen E 5 E of the driving mechanism, substantially as shown and described, and for the purpose set forth.

In testimony that I claim the foregoing I

have hereunto set my hand at Milwaukee, in the county of Milwaukee and State of Wisconsin, in the presence of two witnesses.

WILHELEM PROCHNOW.
